UNITED STATES PATENT OFFICE.

JOHN A. McWILLIAMS, OF PHILADELPHIA, PENNSYLVANIA.

PACKING AND DISPLAY BOX.

1,413,677.

Specification of Letters Patent. Patented Apr. 25, 1922.

Application filed December 29, 1920. Serial No. 433,787.

To all whom it may concern:

Be it known that I, JOHN A. McWILLIAMS, a citizen of the United States, residing in the city and county of Philadelphia, State of Pennsylvania, have invented a new and useful Packing and Display Box, of which the following is a specification.

My invention consists of a box formed of members adapted to form a knock down body for packing purposes thereof, and to place said body in inclined or tilted position for displaying its contents to the best advantage.

The invention is satisfactorily illustrated in the accompanying drawing, but the important instrumentalities thereof may be varied, and so it is to be understood that the invention is not limited to the specific details shown and described, as long as they are within the spirit or scope of the claims.

Figure 1 represents a perspective view of a box embodying my invention.

Figure 2 represents an end view thereof.

Figure 3 represents a transverse vertical section thereof on line 3—3 Figure 1.

Figure 4 represents a longitudinal section thereof on line 4—4 Figure 1.

Figure 5 represents a longitudinal section on line 5—5 Figure 4.

Figure 6 represents a side elevation of flaps employed for locking the ends proper of the body of the box.

Figure 7 represents a plan view of the sheet from which the body of the box is formed, said sheet being preferably formed of paper or paper material.

Similar numerals of reference indicate corresponding parts in the figures.

Referring to the drawings.

1 designates the bottom of the body of the box. 2 designates the sides thereof, and 3 designates the ends thereof, the sheet being properly scored on the lines 4 and 5 respectively to permit said sides and ends to be turned up from the bottom 1.

Continuous of the sides 2 are the flaps 6 which are adapted to fold inwardly towards each other on the score lines 7 and again on the ends 3, they being formed with slits 8 whose walls are adapted to interlock so as to prevent the sides 2 from opening or spreading laterally.

Continuous of the ends 3 are the auxiliary folds 9 which may be turned down into the body of the box on the score lines 10, thus

doubling the ends and strengthening the same. Continuous of one of the folds 9 is the short supplemental fold 11 which forms a tongue adapted to be turned upon the bottom 1 of the box on the score line 11⁶⁰ and interlock therewith as will be herein-after more fully described.

Continuous of the other fold 9 is a long flap 12 which may be turned up from said fold 9 on the bottom score line 13 and extend upwardly from the body so as to present a surface above the top of the box for indicating the contents of the body of the box and for advertising purposes, said fold 12 being, however, adapted to be lowered 70 and placed upon the bottom of the box as shown in dotted lines Figure 4.

In the bottom are lips 14 and 15, the lip 14 forming a lip adapted to have the short fold 11 tucked thereunder and so locked as 75 to prevent the adjacent end 3 of the body and the connected fold 9 from opening and spreading outwardly.

About the score line 13 is the tongue 16 which is cut out from the flap 12 and adapted 80 to be tucked under the lip 15 and so locked as to prevent the adjacent end of the body from opening and spreading outwardly.

By these means the sides and ends of the body when set up are retained in their operative positions. Continuous, outwardly from the sides 2 are the folds 17 which are adapted to be turned down on said sides on the score lines 18 and rest against said sides thus doubling the latter and strengthening 90 the same.

Continuous outwardly from the folds 17 are the supplemental folds 19 between which and the folds 17 are the oblique score lines 20 whereby the folds 19 may be turned under 95 the bottom 1 of the body while the lower edges 21 of the folds 17 are oblique whereby the body 1 is placed in inclined position on its support and so may display its contents to the best advantage, for inspection or examination, while the folds 19 under the bottom 1 in a measure strengthen the latter and as the weight of the body is on said folds 19 it serves to hold the latter in position and so prevent the folds 17 from spreading apart. 100

Continuous of the ends of the folds 17 are the folds 22 which may be turned towards each other on the score lines 23 against the adjacent end of the body of the box. In said folds 22 are the slits 24 and 25 the walls of 110

which are adapted to engage thus interlocking said folds and preventing the folds 17 from spreading apart from the sides 2.

It will be seen that when the various folds 5 are assembled the sides and ends of the box are strengthened and interlocked, preventing disintegration of the body, while the fold 12 presents itself above the top of the box to 10 present new matter that is placed therein indicative of the contents of the box and for advertising purposes, while the body stands at an inclination being higher at its head end than at the opposite end for the purpose stated.

15 The original sheets shown in Figure 7 may be placed one on the other ready to be taken up and converted into a box of the order stated, and when the box as such is not required its members may be disconnected, 20 spread-out and knocked down again placing the sheet in flat condition.

The sheets primarily may be piled one on the other. When the body of the box is occupied, the upper portion of the flap 12 may 25 be bent down over the contents of the same as a partial cover therefor, while the lower portion thereof remains on the body without liability to fold.

When the body is set-up without being 30 tilted, the folds 17 and 19 may be turned inwardly and down over the top of the body, thus constituting the lid of the box and so closing the latter whereby the contents thereof are covered and protected from exposure 35 and prevented from escaping from the body.

Having thus described my invention what I claim as new and desire to secure by Letters Patent, is:—

1. A box formed of a piece of suitable material and embodying a bottom, sides and ends, additional folds on said sides and ends adapted to turn down into the body of the box, double the ends and to reinforce the same, supplemental folds on said ends adapt-

ed to be interlocked with the bottom of said body to retain said ends in operative position, and supplemental folds on said sides adapted to be interlocked with each other over said ends and retain said sides in operative position, a flap adapted to be turned up for advertising purposes, and means for holding said flap down in the box. 45 50

2. A box formed of a piece of suitable material and embodying a bottom, sides and ends, additional folds on said sides and ends adapted to turn down into the body of the box, double the ends and to reinforce the same, supplemental folds on said ends adapt- 55 60 65

ed to be interlocked with the bottom of said body to retain said ends in operative position, supplemental folds on said sides adapt- 70 75

ed to be interlocked with each other over 80

said ends and retain said sides in operative position, a flap adapted to be turned up for advertising purposes, and a tongue cut out from said flap and adapted to engage the bottom to prevent the adjacent end of the body from opening and spreading outwardly.

3. A box formed of a piece of suitable material and embodying a bottom, sides and ends, additional folds on said sides and ends adapt-

ed to turn down into the body of the box, double the ends and to reinforce the same, supplemental folds on said ends adapt-

ed to be interlocked with the bottom of said body to retain said ends in operative position, supplemental folds on said sides adapt-

ed to be interlocked with each other over said ends and retain said sides in operative position, a flap adapted to be turned up for advertising purposes, a tongue cut out from said flap adjacent its lower end, and a lip on the bottom for cooperation with said tongue. 75 80 85
